UNITED STATES PATENT OFFICE.

WILLIAM S. BROWN, OF DEERFIELD, INDIANA.

ICE-SHAVER.

No. 903,053.

Specification of Letters Patent.

Patented Nov. 3, 1908.

Application filed May 28, 1907. Serial No. 376,142.

To all whom it may concern:

Be it known that I, WILLIAM S. BROWN, a citizen of the United States, residing at Deerfield, in the county of Randolph, State of Indiana, have invented certain new and useful Improvements in Ice-Shavers; and I do hereby declare the following to be a full, clear, and exact description of the invention, such as will enable others skilled in the art to 10 which it appertains to make and use the same.

This invention has relation to ice-shavers of the class combining with them a hollow body or reservoir in which the ice cut off by 15 a planing bit is adapted to be collected to be removed and used as desired.

The object of the invention is to provide improvements in the class of devices referred to which will render them more efficient and 20 generally serviceable than heretofore.

The nature of the invention is fully and clearly ascertainable from the device portrayed in the annexed drawings, forming a part of this specification, in view of which it 25 will first be described with respect to its construction and mode of operation and use, and then be pointed out in the subjoined claim.

Of the said drawings—Figure 1 is a side elevation of the improved contrivance. Fig. 30 2 is a plan. Fig. 3 is a bottom view. Fig. 4 is a vertical longitudinal section. Fig. 5 is a horizontal section. Fig. 6 is a perspective view of the bit detached, showing the form of the chipping or planing teeth. Fig. 7 is a transverse section.

Similar characters of reference designate similar parts or features, as the case may be, wherever they occur.

In the drawings 1 designates a casing of 40 metal cast or stamped up to form an elongated body with a practically flat top 2 and the stub bottom 3, and sides 4 that incline from their upper edges inward to the bottom. The top has an opening 5 formed in it that 45 may be closed with a hinged lid 6 when the device is in use, and opened when it is desired to discharge its contents. The stub bottom 3 covers the forward end of the casing as shown in Fig. 4.

The rear end terminates short of the sides 50 4, as shown at 7 in Fig. 4, and the extension of the sides below the terminal line of the rear end are provided with rounded apertures or holes 8 at the rear and short slots 9, 55 forward of said apertures. The edge 7

serves as a stop to the bit 10 as shown in Fig. 4.

10 designates the shaving bit that is constructed of a stout steel plate and is provided on its forward end with sharply pointed teeth 11 having inclined sides 12 which are beveled on their upper sides so that the lower sides or edges shall present a sharp cutting edge from the point to the base of the teeth.

The forward portion of the bit bearing the 15 teeth 11 is offset downward as at 13, so that the forward end bearing the teeth extends at a different plane from the body portion, the width of the bit being such as to permit it to be clamped between the sides of the 20 body at the bottom. The said clamping connection is effected by placing the bit between the sides, with its rear portion extending beyond the lower rear stop edge 7 of the 25 casing and resting at its upper surface there- 75 against, as shown.

By providing the bit with an offset and extending the offset ice-shaving end portion in a different plane from the body portion, the former can be more readily supported so 30 as to bring it in the plane of its movement and hence be made to shave the ice more easily, as will be readily understood.

14 and 15 designate headed bolts that are 35 screw-threaded on the ends opposite to the heads adapting them to have nuts turned thereon. The clamping bolt 14 is passed through the round holes 8 at the rear of the sides and the clamping bolt 15 is in like manner engaged with the short vertically disposed slots 9 in said sides intermediate of their ends, the body of the bit 10 being arranged above the said bolts and resting thereon between the said lower edges of the sides 4. With the parts in this position the nuts 45 on the bolts are turned up tightly securing the bit in clamped position between the lower rear margins of the sides. The offset 13 in the bit is of such form that when the body of the bit is clamped in place as explained the 50 teeth on the forward edge of the bit will extend in the plane of the body of the device, and the slots 9 in the sides provide for fixing the bolt 15 in a lower or higher plane so as to have the shaving teeth cut deeper or shallower in the ice.

Connected with the rear edge 16 of the forward portion of the bottom 3 is a spring plate, 17, of steel, brass, or other suitable metal which is extended from the stub bot- 55 105 110

tom 3 and the rear portion of which rests on top of the teeth 11 and projects to or near to their bases. While the said spring plate is not connected at its sides with the sides of 5 the body of the device, and is permitted to play vertically at its free end between the latter sides, it is given no more space than will secure it from binding in place.

The bit, its teeth, and the parts for rendering it adjustable and coöperating with it are important features of the invention, and these as well as other parts may be varied in form and arrangement so long as they accomplish substantially the same result as is 10 ascribed to them.

In use, with the parts in position as specified the device can be placed on a piece of ice as one would place a carpenter's plane to plane a board, but instead of moving it with 20 long strokes it may be given short jerky strokes which will chip off the ice in fine pieces, which latter will slide over the teeth of the bit into the hollow body until a sufficient quantity is collected therein, when by 25 the opening of the lid 6, the chipped pieces can be discharged for use as desired.

The reason for making the sides inclined as desired is that the chipped ice collected in the hollow body, may not bind or clog in the 30 bottom.

When the points or sharpened edges become dulled, if such thing should occur, they may be sharpened by the use of a small file.

What is claimed is—

In an ice shaver of the character described, 35 the combination with a casing having a stub bottom near its forward end, the rear end terminating a suitable distance above the bottom edge of the casing to form a stop edge, and with perforations in the sides of 40 the casing below said stop edge and a vertically disposed slot intermediate of its ends, a clamping bolt held within said perforations, a clamping bolt held within said slot, a shaving bit provided with an offset so that its 45 cutting edge occupies a plane nearly coincident with that of its motion, said bolt engaging the bit at its offset portion to hold the same in place, said bit being carried by said bolts and resting against said stop edge, 50 and a spring plate extending from said stub bottom and resting upon said bit, as set forth.

In testimony whereof, I affix my signature, in presence of two witnesses.

WILLIAM S. BROWN.
